UNITED STATES PATENT OFFICE.

SIDNEY MOORE, OF PHILADELPHIA, PENNSYLVANIA, ASSIGNOR OF THREE-FOURTHS TO JOSEPH HENRY MOORE, OF PHILADELPHIA, PENNSYLVANIA, AND ALFRED HALL RYAN, OF TRENTON, NEW JERSEY.

AUTOMATIC FILLING-LOCK.

SPECIFICATION forming part of Letters Patent No. 687,433, dated November 26, 1901.

Application filed February 2, 1901. Serial No. 45,775. (No model.)

To all whom it may concern:

Be it known that I, SIDNEY MOORE, a citizen of the United States, residing at Philadelphia, in the county of Philadelphia and State 5 of Pennsylvania, have invented a certain new and useful Automatic Filling-Lock, of which the following is a specification, reference being had therein to the accompanying drawings.

10 This invention relates to looms; and the object in view is to provide an automatic filling-lock arranged contiguous to the race-way and adapted to automatically separate and successively raise and lower the filling- 15 threads at proper intervals during the movements of the shuttles, so as to hold elevated or depressed under tension the filling-threads that are not in use at the particular moment, thus obviating the liability of the shuttle 20 gaging and becoming entangled with the remaining filling-threads and drawing the same into the cloth.

The object of the invention is to provide 25 simple and reliable mechanism adapted to be applied to looms of ordinary construction arranged at or near the end of the lay and adjacent to the tier of drop shuttle-boxes adapted to raise and lower and securely hold the 30 different filling-threads above or beneath the raceway as the different shuttles are thrown back and forth, the mechanism comprising a series of fingers which are automatically moved upward or downward as the drop 35 shuttle-boxes are raised and lowered, the operating mechanism for the fingers being controlled by the movements of the drop shuttle-boxes.

With the above and other objects in view, which will be more fully understood as the 40 nature of the invention is set forth, the invention consists in the novel construction, combination, and arrangement hereinafter fully set forth, illustrated, and claimed.

In the accompanying drawings, Figure 1 is 45 a side elevation of one end of the lay of a loom, showing the invention applied thereto. Fig. 2 is an enlarged detail perspective view of the automatic filling-lock. Fig. 3 is a plan view of the same. Fig. 4 is a detail perspective view showing the operative connection

between the drop shuttle-boxes and the arm of the operating-lever. Fig. 5 is a detail horizontal section showing the manner of adjusting the fulcrum of the operating-lever.

Similar numerals of reference designate corresponding parts in all figures of the drawings.

In the drawings I have illustrated one end of the lay of a loom, in which 1 designates a portion of a loom side; 2, the arch; 3, the lay; 4, the lay end casting, and 5 a tier of drop shuttle-boxes.

6 designates the lay-sword, which is connected at its lower end to the rocker-shaft 7, said rocker-shaft having connected thereto 65 the rocker-iron 8.

9 designates the shuttle-box lifter-rod, supported at its lower end by the rocker-iron and encircled by a coiled spring 10, the lifter-rod having at its upper end the usual lifter-fork 11, extending downward from the drop 70 shuttle-boxes 5.

12 designates the box-chain, which is connected at its lower end to the lifter-rod 9 and passes over a sheave 13, supported on a 75 bracket connected with the lay end casting, said chain forming the means for automatically operating the shuttle-boxes in a manner well understood by those familiar with the art to which this invention appertains. 80

In carrying out the present invention I provide a supporting-plate 14, which is secured in any convenient manner to a standard 15, extending upward at one side of the race-plate 16, which forms the bottom of the race-way over which the shuttles move. At a suitable point the race-plate is provided with a transverse depression 17, and above said depression is arranged a bearing-plate 18, which may be supported at one end by a post 90 or standard 19, extending upward from the race-plate, and at its opposite end by horizontally-extending arm or brace 20, having a slotted and adjustable connection at 21 with the supporting-plate 14. 95

Extending laterally and outward from the plate 14 is a stud 22, forming a common fulcrum for a series of oscillatory arms 23, three of such arms being shown, and each arm being provided with a terminal finger 24, all of 100

said fingers extending at right angles to their respective arms and being arranged in parallel relation to each other, as clearly shown in Fig. 2. The fingers when in their lowest positions are adapted to be received in the depression 17 in the race-plate, and when elevated they are received in parallel grooves 25 in the lower surface of the bearing-plate 18. The said lower surface of the bearing-plate 18 and also the grooves 25 are lined with leather, cloth, or other textile or similar material, as shown at 26, in order to obtain the necessary frictional hold on the filling-threads and prevent them from being injured and severed when held firmly against the bearing-plate by the fingers 24.

Each of the levers 23 is provided at the opposite side of its fulcrum with a heel extension 27, with which one of the engaging portions of an operating-lever 28 engages. Said lever is fulcrumed on a stud 29, which is connected with the supporting-plate 14. At one end and on one side of its fulcrum the lever 28 is provided with stepped engaging portions 30, which are adapted to successively come in contact with the heel extensions of the oscillatory arms 23 for depressing said heel extensions and raising the fingers 24 into contact with the bearing-plate 18, at the same time lifting the filling-threads supported by said fingers. At this point it may be stated that any number of fingers may be employed, according to the number of filling-threads, and that one less finger is employed than the number of filling-threads. It will be noted that the steps 30 of the lever are arranged in the same planes with the heel extensions 27, so that each engaging portion can only operate upon its respective arm 23. It will further be seen that the outer surface 31 of the operating-lever is concentric to the axis of movement thereof and that each of the heel extensions is provided with a concaved dwell-surface 32, so that after an engaging portion 45 of the lever has acted upon its respective arm 23 and raised the finger 24 thereof the concentric outer surface 31 of the lever will bear and move against the dwell-surface 32, thus holding the arm 23 stationary with the finger 50 24, holding one of the filling-threads against the bearing-plate. It will also be seen that by providing the lever with the stepped engaging portions there is a dwell between the successive movements of the several fingers, 55 giving time for the shuttle-box to move back and forth.

The fulcrum-stud 29 is made adjustable with respect to the supporting-plate 14, as shown in the detail sectional view Fig. 5, in which it will be seen that the lever is provided with the sleeve 33, through which the stud passes, and the plate 14 is provided with a slot 34 to receive the reduced inner end or shank 35 of the stud, the stud being provided 60 with a shoulder 36 to obviate any binding of the operating-lever 28, which shoulder bears against the plate 14. The fulcrum-stud 29

may be adjusted toward and away from the stud 22, on which the arms 23 are mounted, by moving the stud lengthwise of the slot 34, 70 and the adjustment may be fixed by means of the nut 37, which bears against the inner side of the plate 14. By providing the adjustable fulcrum-stud the throw of the oscillatory arms and the fingers carried thereby 75 may be regulated to agree with the distance between the race-plate and the bearing-plate. The lever 28 is also provided with an operating-arm 38, which is pivotally connected thereto at 39 and adjustable relatively to the 80 lever by means of a clamping-screw 40, which passes through a curved slot 41 in the lever 28 and engages a threaded opening in the operating-arms 38. The object of this adjustment is to adapt the operating-arm to the 85 position of a swivel-head 42, which is carried by a bracket or attaching-plate 43, adapted to be secured to one of the drop shuttle-boxes, and preferably the upper one thereof, as shown in Figs. 1 and 4. The head 42 has a 90 swiveled connection with the bracket 43 and is provided with a slot or opening 44, in which the operating-arm 38 is slidably received, whereby as the drop shuttle-boxes are raised and lowered the operating-arm 38 is caused 95 to move in a corresponding direction, thus rocking the operating-lever and causing it to successively actuate the oscillatory arms 23, with the result that the fingers 24 are moved upward and downward one after the other 100 for the purpose of separating the filling-threads carried thereby and moving said threads alternately upward and downward, so as to hold them under tension and out of the way of the traveling shuttle. In this way 105 all of the threads are held under tension and out of the path of the shuttle, with the exception of the particular thread upon which the shuttle is operating, thus obviating the danger of the shuttle becoming entangled 110 with the several filling-threads and drawing the same into the cloth.

The device hereinabove described may be placed on all kinds of looms for textile weaving and may be employed in connection with 115 any number of boxes, circular or otherwise. The use of the automatic filling-lock hereinabove described will be productive of cleaner and more even cloth, will obviate a large amount of filling-cutting, and will prevent the 120 dirt spots, commonly called "shuttle-marks," by reason of the filling being held tightly by the fingers and the shuttle prevented from coming in contact therewith. By the use of this filling lock the manufacturer can do away 125 with the steam-box commonly used to take the curl out of the filling, enabling him to put any amount of twist in the filling without danger of the filling being drawn into the cloth to the injury thereof. It is also productive of more even selvage and will effect a great saving in the burling of the cloth. The cloth produced will also be more uniform in width, and a considerable saving in mate-

rial will be effected by preventing the filling strands or threads from becoming looped and worked into the cloth.

I do not desire to be limited to the exact details of construction hereinabove set forth, and accordingly reserve the right to change, modify, or vary the construction within the scope of this invention.

Having thus described the invention, what I claim as new, and desire to secure by Letters Patent, is—

1. A filling-thread lock for looms, comprising a series of pivoted arms fulcrumed above the plane of the race-plate and carrying fingers for successively raising and lowering the filling-threads, and an operating-lever adapted to successively actuate said arms.

2. A filling-thread lock for looms, comprising a series of pivoted arms carrying fingers for successively raising and lowering the filling-threads, and an operating-lever fulcrumed above the plane of the race-plate and adapted to successively actuate said arms, the latter being provided with dwell-surfaces, for the purpose stated.

3. A filling-thread lock for looms, comprising a series of pivoted arms carrying rigidly-attached fingers for successively raising and lowering the filling-threads, and an operating-lever having stepped engaging portions for successively actuating said arms.

4. A filling-thread lock for looms, comprising a series of pivoted arms carrying fingers for successively raising and lowering the threads, and an operating-lever having stepped engaging portions for successively actuating said arms, and a concentric outer surface which coöperates with the dwell-surfaces on said arms.

40 5. A filling-thread lock for looms, comprising a series of pivoted arms carrying fingers for successively raising and lowering the filling-threads, and also provided with heel extensions having dwell-surfaces, and an operating-lever having stepped engaging portions for successively actuating said arms and a

concentric surface which coöperates with said dwell-surfaces.

6. A filling-thread lock for looms, comprising a series of pivoted arms carrying fingers 50 for successively raising and lowering the filling-threads, and an operating-lever adapted to successively actuate said arms, the latter being provided with dwell-surfaces and the lever having concentric dwell-engaging surfaces of different lengths.

7. A filling-thread lock for looms, comprising a series of pivoted arms of different lengths carrying rigidly-attached fingers for successively raising and lowering the filling-threads, 60 a bearing-plate for the fingers, and an operating-lever adapted to successively actuate said arms.

8. A filling-thread lock for looms, comprising a series of pivoted arms carrying rigidly-attached fingers for successively raising and lowering the filling-threads, and an operating-lever adapted to successively actuate said arms, said lever being operatively connected directly with one of the drop shuttle-boxes 70 and actuated thereby.

9. A filling-thread lock for looms, comprising a series of pivoted arms carrying fingers for successively raising and lowering the filling-threads, an operating-lever adapted to successively actuate said arms, and an operating-arm adjustably connected to the lever.

10. A filling-thread lock for looms, comprising a series of pivoted arms carrying fingers for successively raising and lowering the filling-threads, an operating-lever adapted to successively actuate said arms, and a swivel-head connected with one of the drop shuttle-boxes and coöperating with an arm of the operating-lever.

In testimony whereof I affix my signature in presence of two witnesses.

SIDNEY MOORE.
